(57) **CLAIM**

The ornamental design for a baton, as shown and described.

DESCRIPTION

FIG. 1 is a perspective view of the baton;

FIG. 2 is a bottom plan view of the baton;

FIG. 3 is a first end elevational view of the baton;

FIG. 4 is a side elevational view of the baton;

FIG. 5 is a second end elevational view of the baton;

FIG. 6 is a top plan view of the baton; and,

FIG. 7 is a cross-sectional view of the baton, taken along line 7—7 of FIG. 1.

The grip, butt ends, and certain openings on the baton are shown in uneven broken lines for illustrative purposes only and form no part of the claimed design.
